US00D575668S

(12) **United States Design Patent**
Rashid et al.

(10) **Patent No.:** **US D575,668 S**
(45) Date of Patent: **** Aug. 26, 2008**

(54) **PLANT CONTAINER**

(75) Inventors: **Karim Rashid**, New York, NY (US);
Treg C Bradley, Phoenix, AZ (US)

(73) Assignee: **Grobal, L.L.C.**, Chandler, AZ (US)

(**) Term: **14 Years**

(21) Appl. No.: **29/278,391**

(22) Filed: **Mar. 28, 2007**

(51) **LOC (8) Cl.** **11-02**

(52) **U.S. Cl.** **D11/152**

(58) **Field of Classification Search** **D6/403, D6/556; D11/143-148, 152-156; D19/77, D19/81, 84; D26/9; D34/1-11; D99/5, D99/19; 47/32.7, 39, 41.01, 41.1, 41.12-41.15, 47/44-47, 65.5, 66.1, 66.6, 66.7, 67-71**

(57) **CLAIM**

The ornamental design for a plant container, as shown and described.

DESCRIPTION

FIG. 1 is a perspective view of a plant container showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded, perspective view thereof; and,

FIG. 9 is an exploded, left side elevation view thereof.

The broken lines depict environmental subject matter only and form no part of the claimed design.
